UNITED STATES PATENT OFFICE

INA BELLE KIMMEL, OF JAMESTOWN, NEW YORK

CURLING ROD HAIR WINDER

Application filed March 17, 1931. Serial No. 523,335.

The present invention relates to hair curling devices and more particularly to a device to facilitate winding of hair on curling rods used in the process commonly known as the permanent wave process.

An object of this invention is to provide a winding device which may be used in combination with conventional curling members, which is so constructed as to wind the hair on the curling members in an even and tight manner.

Another object of this invention is to provide a device of this kind which is so constructed that when the winder has reached the end of the hair it will wind the ends of the hair about the curling member and hold the ends in tight position about the hair so as to permit the winding of securing means about the ends of the hair for curling the ends of the hair at the same time that the body of the hair is curled.

A further object of this invention is to provide a device of this kind which is so constructed that it may be used for what is commonly termed back winding, so as to curl the hair between the already curled portion and the head of the individual which portion has grown out in uncurled form.

A still further object of this invention is to provide a device of this kind which will effectively curl the ends of the hair in what is termed ringlets during the one operation of curling the hair for the permanent wave.

The above and various other objects and advantages of this invention will in part be described in and in part be understood from the following detailed description of the present preferred embodiment, the same being illustrated in the accompanying drawings, wherein:

Figure 1 is a detail top plan view of a device constructed according to the preferred embodiment of this invention;

Figure 2 is a detail side elevation of the device;

Figure 3 is a longitudinal section taken substantially through the longitudinal center of the device;

Figure 4 is a detail view showing the device in open position;

Figure 5 is a sectional view taken on the line 5—5 of Figure 3;

Figure 6 is a sectional view taken on the line 6—6 of Figure 3, and

Figure 7 is an enlarged fragmentary view taken on the line 7—7 of Figure 5.

Referring to the drawings wherein like numerals of reference designate corresponding parts throughout the several views, the numeral 10 designates one-half of a winder barrel and the numeral 11 designates the other or upper half of the winder barrel, the half portions 10 and 11 being constructed in semi-cylindrical form so that when they are placed together, a substantially cylindrical barrel will be formed.

The barrel sections 10 and 11 are hingedly secured together by a hinge 13 and the section 11 is provided with a pivoted catch 12 which engages in a keeper 14 on the section 10 so as to lock the two sections together. The barrel sections 10 and 11 are each provided with a slidably guide member 15, the guide member 15 having an outstanding lug 16 which engages in a longitudinally disposed groove 17 in the barrel sections 10 and 11, and an expansible spring 18 is mounted in the groove 17 and engages the lug 16 so as to constantly urge the guide member 15 toward one end of the barrel sections 10 and 11. Stop lugs 19 are provided in the barrel sections 10 and 11 so as to limit the movement of the guide member 15 in one direction. The barrel sections 10 and 11 are also provided adjacent the central portion thereof with inwardly extending flanges 20 which engage the free edges of the guides 15 so as to hold these guides 15 against rotary movement or withdrawal from the barrel sections 10 and 11.

The guides 15 are constructed in substantially semi-cylindrical form having a transversely disposed supporting portion 21 which is provided with a substantially semi-circular recess 22 for receiving the periphery of a curler rod and a pair of crossed resilient supporting members 23 are secured at one end to the transverse member 21 and the opposite end is free, these springs or resilient members 23 being adapted to permit the use of curling rods of various sizes and to hold

these rods concentrically of the barrel sections 10 and 11.

A back winding guide 24 is slidably mounted within the barrel section 11, this guide 24 being of a construction similar to the guides 15, but having a lug 25 extending forwardly and downwardly therefrom and slidably engaging in a groove or slot 26, and is constantly urged rearwardly by means of an expanding spring 27 which is mounted within the slot 26.

A locking member 28 is slidably mounted on the exterior of the barrel section 11, this locking member 28 having an inwardly extending lug 29 at one end thereof which engages the lug 25 so that when the locking member 28 is moved longitudinally of the barrel section 11, the guide member 24 is moved forwardly and is held in a position where one end thereof is flush with a recess 30 in one end of the barrel section 11. This guide member 24 will prevent the hair from winding into the body of the barrel sections 10 and 11 when the hair is being wound outwardly from the head of the individual, but when the hair is being wound inwardly from the free ends thereof, the guide member 24 is released from its forward position, and the spring will then urge the guide 24 rearwardly so as to permit the hair to wind about the curler rod within the interior of the barrel sections 10 and 11. This operation constitutes the back winding of the hair on the curler rod.

35 The guide 24 is also provided with centering springs 23 so as to secure the curler rod within the barrel sections 10 and 11. A plate 31 is mounted on the barrel section 11 at the forward end thereof and covers the major portion of the spring slot 26 and the spring 27.

The barrel section 10 at the forward end thereof is provided with a resiliently mounted curler engaging member generally designated as 32 which extends transversely of the barrel section 10 and is provided with a centrally disposed and longitudinally extending recess 33 for engagement with the curler and the hair wound about the curler, and a spring 34 constantly urges the plate 32 inwardly and into engagement with the curler and the hair disposed about the periphery of the curler.

The plate 32 is provided at the opposite edges thereof with depending flanges 35 which limit the inward movement of the tensioning member 32. The tensioning member 32 is disposed oppositely of the slot 30 in the barrel section 10, and this barrel section 10 is provided with a pivoted hair guiding member 36 which is pivotally mounted on a lug 37 and a spring 38 engages the hair guiding member 36 so as to constantly urge this guiding member 36 into open position. The barrel is provided adjacent the notch or recessed portion 30 with an outstanding lug or stop

member 39 which is adapted to hold the hair guide 36 in a closed position.

When the guide 36 is in closed position, one edge of the guide is disposed in spaced relation to the adjoining edge of the slot 30, thereby providing an elongated narrow slot 70 which is provided so as to spread the hair out in a ribbon-like form for winding on the curler rod mounted within the barrel sections 10 and 11. The stop member 39 is so 75 constructed that when the hair guiding member 36 is moved into closed position, the lower face of the member 36 will ride over the tapering surface of the stop 39 and be held in closed position by the upstanding edge 80 of the stop 36.

In the use of this device, the curler rod 40 is attached at one end in the usual manner to the hair and the hair is then passed through the recess 30 with the guide member 85 36 in open position. The barrel sections 10 and 11 will, of course, be opened so as to dispose or mount the curler rod 40 longitudinally and concentrically of the barrel sections, whereupon the barrel sections 10 and 11 may be closed and locked by means of the latch member 12. The guide or hair spreading member 36 may then be moved to closed position so as to provide a relatively narrow slot or passageway for the hair which will 90 spread the hair into a ribbon-like form. The barrel sections 10 and 11 may then be rotated about the curler rod 40 until the entire length of the hair is wound upon the periphery of the curler rod. During the winding operation, the barrel sections 10 and 11 will be moved longitudinally of the curler rod, the hair being wound on the rod in spiral-like form. When the end of the hair is reached, the rotation of the barrel sections 10 and 11 95 may be stopped and a section of string 100 passed through a string guiding member 41 which is mounted on the pivoted guide member 36, one end of the string guiding member 41 being free and frictionally engaging the guide member 36 so as to permit the string to be slipped beneath the string holding member 41. The barrel sections 10 and 11 may then be further rotated 110 about the curler rod 40, which rotation will tightly wind the string about the free ends of the hair so as to hold the hair into contact with the periphery of the curler rod 40.

If desired, at the same time the string is being wound about the ends of the hair, a 120 gauze tape may be passed through the slot formed between the guide 36 and the recess 30, and the barrel sections 10 and 11 rotated about the curler rod 40, which operation will 125 not only wind the tape about the ends of the hair, but wind the string on top of the tape. The tensioning member 32 will act to prevent unwinding of the curler rod 40 with the hair mounted thereupon so that the rotation of the barrel sections 10 and 11 may be stopped 130

at any desired point and the hair will not unwind from the curler rod. This is of particular advantage when the end of the hair is reached, as the tensioning member 32 will hold the ends of the hair against the periphery of the curler rod 40 and permit the winding of tape or string about the ends of the hair so as to bind the ends of the hair.

During the winding of the hair on the curler rod by means of the device herein disclosed, the guide member 24 is disposed with one end adjacent the edge of the slot or cut out portion 30 so as to prevent the hair being wound on the curler rod from entering the body of the barrel sections 10 and 11. Through the use of this device, when the hair is being wound on the curler rod 40, the barrel sections 10 and 11 may be so rotated as to cause the hair being wound on the curler rod to be wound in overlapped relation or in straight spiral form, depending on the character of the curl which it is desired to form in the hair.

When it is desired to back wind the hair, that is, to start at the outer end of the hair and wind the hair on the curler rod 40 toward the head of the individual, the free ends of the hair may be tied or wrapped on the curler rod 40 and the barrel sections 10 and 11 disposed about the rod 40 with the guide member 24 in released position so as to permit the hair to wind inwardly of the barrel sections 10 and 11 between the end of the released guide member 24 and the slot formed between the pivoted member 36 and the edge of the cut-out portion 30.

It will be obvious from the foregoing that an exceedingly simple winder has been disclosed by means of which the winder may be removably mounted about the curler rod, and when the hair has been wound upon the curler rod, the winder may be readily released therefrom and used on other curler rods so that it is only necessary to use one curler rod for the winding operations.

By mounting the guide members 15 in slidable relation with respect to the barrel sections 10 and 11 when the enlarged end 42 of the curler rod is drawn inwardly of the barrel sections 10 and 11, the enlarged end portion 42 will move the slidable guide members 15 inwardly coactive with the inward movement of the enlarged portion 42. This enlarged portion 42 is provided in certain curling rods for the purpose of tightening the hair upon the curler rod, particularly after the ends of the hair have been secured about the rod.

It is, of course, understood that various changes and modifications may be made in the details of construction and design of the above specifically described embodiment of this invention without departing from the spirit thereof, such changes and modifications being restricted only by the scope of the following claims.

I claim:

1. A hair winder of the character described comprising a cylindrical barrel adapted to be removably and rotatably disposed about a hair curling rod, guide means within the barrel for holding the rod concentrically within said barrel, and a tensioned member carried by said barrel and engaging the periphery of the curler rod whereby to tighten the hair on the curler rod during the rotation of the barrel about the curler rod.

2. As a new article of manufacture, a hair winding device of the character described comprising a cylindrical barrel adapted to removably and rotatably engage about a hair curling rod, guide means disposed within the barrel, and resilient means carried by the guide means and adapted to engage the periphery of the rod whereby to hold the rod concentrically within the barrel.

3. As a new article of manufacture, a hair winder of the character described comprising a pair of semi-cylindrical barrel sections, means for hingedly securing said sections together, means for locking said sections together whereby to provide a cylindrical winder, guide means within each barrel section and engaging the periphery of a curler rod removably disposed within the barrel sections, and means carried by said guide means for holding the curler rod concentrically within the barrel sections when in closed position.

4. As a new article of manufacture, a hair winder of the character described comprising a pair of semi-cylindrical sections, means for hingedly securing said barrel sections together, locking means for holding said barrel sections in closed position whereby to provide a substantially cylindrical winder barrel, guide means mounted in each of said barrel sections, means for slidably mounting said guide means within each barrel section, and resilient means carried by the barrel sections and engaging the guide means whereby to constantly urge the guide means toward one end of each barrel section.

5. As a new article of manufacture, a hair winder of the character described comprising a pair of semi-cylindrical barrel sections, means for hingedly securing said sections together, locking means for locking said barrel sections in closed position whereby to provide a substantially cylindrical winder barrel, slidable guide means mounted in each of said semi-cylindrical barrel sections and adapted to engage the periphery of a curler rod whereby to hold the curler rod concentrically within the barrel sections when in closed position, and a tensioned guide member carried by one of said semi-cylindrical barrel sections and movable transversely of the barrel section whereby to resiliently engage the periphery of the curler rod for tightening the hair on the rod during the rotation of the winder about the periphery of the curler rod.

6. As a new article of manufacture, a hair winder of the character described comprising a pair of semi-cylindrical barrel sections, means for hingedly securing said sections together, a keeper carried by one of said sections, a pivoted latch carried by the other of said sections and engaging said keeper whereby to hold said barrel sections in closed position about the periphery of a curler rod 5 disposed between the barrel sections, and tensioned guide means carried by said barrel sections and engageable with the periphery of the curler rod whereby to hold said curler rod concentrically within the barrel sections 10 when in closed position and coercively tighten the hair about the curler rod.
7. As a new article of manufacture, a hair winder of the character described comprising a cylindrical barrel, guide means slidably mounted within the barrel and adapted to engage the periphery of a hair curling rod disposed within the barrel, pivoted hair guiding means carried by said barrel, and hair tightening means carried by said barrel and engaging the periphery of the curler rod whereby to tighten the hair upon the curler rod upon rotation of the barrel about the rod. 15
8. As a new article of manufacture, a hair winder of the character described comprising a pair of semi-cylindrical barrel sections, means for hingedly securing said sections together, locking means for locking said sections in closed position whereby to provide a substantially cylindrical barrel member, a guide member mounted in each of said barrel sections, means for slidably mounting said guide members in each barrel section, resilient means mounted in each barrel section and engaging each guide member whereby to constantly urge said guide member toward one end of the barrel section, a laterally movable hair tightening member carried by one of said barrel sections, a pivoted hair spreader carried by the other of said barrel sections and disposed oppositely from said hair tighter, resilient means for constantly urging said spreader into open position, a stop lug carried by said other barrel section for holding said spreader in closed position and in spaced relation to one edge of said barrel section, and means carried by said other barrel section and disposed therein whereby to prevent winding of the hair about the curler rod within the barrel member and coercively cause the curler rod to move longitudinally of the barrel member. 20
9. As a new article of manufacture, a hair winder of the character described comprising a pair of semi-cylindrical barrel sections, means for hingedly securing said sections together, locking means for locking said sections together whereby to provide a substantially cylindrical barrel member, a slideable guide member mounted in each of said barrel sections, resilient means mounted in each of said barrel sections and engaging said guide members whereby to resiliently urge said guide members toward one end of each barrel section, stop means for limiting the movement of said guide means in said barrel 25 sections in one direction, a laterally movable hair tightening member carried by one of said barrel sections and adapted to engage the periphery of a curler rod disposed between the barrel sections whereby to tighten the hair about the curler rod upon rotation of the barrel sections, and a hair spreading member carried by the other of said barrel sections and disposed oppositely from said laterally movable tightening member whereby to spread the hair in ribbon-like form upon the periphery of the curler rod upon rotation of the barrel about the rod. 30
10. As a new article of manufacture, a hair winder of the character described comprising a pair of semi-cylindrical barrel sections, means for hingedly securing said sections together, locking means for locking said barrel sections together whereby to provide a substantially cylindrical barrel member, a guide member mounted in each of said barrel sections, means for slidably mounting said guide members in each barrel section, resilient means mounted in each barrel section and engaging each guide member whereby to constantly urge said guide member toward one end of the barrel section, a laterally movable hair tightening member carried by one of said barrel sections, a pivoted hair spreader carried by the other of said barrel sections and disposed oppositely from said hair tighter, resilient means for constantly urging said spreader into open position, a stop lug carried by said other barrel section for holding said spreader in closed position and in spaced relation to one edge of said barrel section, and means carried by said other barrel section and disposed therein whereby to prevent winding of the hair about the curler rod within the barrel member and coercively cause the curler rod to move longitudinally of the barrel member. 35
11. As a new article of manufacture, a hair winder of the character described comprising a pair of semi-cylindrical barrel sections, means for hingedly securing said sections together, locking means for locking said barrel sections together whereby to provide a substantially cylindrical barrel member, guide means slidably mounted within each barrel section, resilient means for constantly urging said guide means toward one end of said barrel sections, stop means for limiting the slideable movement of said guide means, resilient means carried by each guide means whereby to hold a curler rod concentrically within the barrel member, tensioned tightening means carried by one of said barrel sections and movable laterally thereof, said tightening means being adapted to resiliently engage the periphery of the curler rod, a releasable hair spreader carried by the other of said barrel sections, resilient means engaging said hair spreader for resiliently urging said spreader into open position, stop means car- 40

ried by said other barrel section and engaging said spreader whereby to hold said spreader in closed position, and a releasable back winding member mounted in said other barrel section and disposed adjacent said hair spreader whereby upon release thereof to permit the winding of the hair inwardly of the barrel sections.

12. As a new article of manufacture, a hair winding device of the character described comprising a pair of semi-cylindrical barrel sections, means for hingedly securing said sections together, locking means for locking said sections in closed position whereby to 10 provide a substantially cylindrical barrel member, guide means slidably mounted in each of said barrel sections and adapted upon closing thereof to engage the periphery of a curler rod disposed between the barrel sections, tightening means carried by one of said 15 barrel sections and movable laterally thereof whereby to engage the periphery of the curler rod disposed within the barrel member and coactively tighten the hair being wound 20 thereabout, a pivoted hair spreading member carried by the other of said barrel sections, and means carried by said spreader whereby to 25 frictionally engage a flexible member wound about the hair disposed on the curler 30 rod coactively with the rotation of the barrel member about the rod.

13. As a new article of manufacture, a hollow member, means for supporting a curler rod axially of the member and in spaced relation to the inner surface thereof while permitting rotary and longitudinal movement of the member with respect to the rod, and means carried by the member for controlling the direction of the longitudinal movement of the 35 member with respect to the rod.

14. As a new article of manufacture, a hollow member, means for supporting a curler rod axially of the member, and controlling means carried by the member for controlling 40 the direction of the longitudinal movement of the member with respect to the rod, said controlling means including releasable locking means for holding said controlling means in a selected position.

15. As a new article of manufacture, a hollow member, guide means disposed within the member for supporting a curler rod axially of the member while permitting rotary and longitudinal movement of the member with 45 respect to the rod, means for controlling the direction of the longitudinal movement of the member with respect to the rod, and hair guiding means carried by the member whereby to guide strands of hair in a ribbon upon 50 rotation of the member about the rod.

In testimony whereof I hereunto affix my signature.

INA BELLE KIMMEL.
